(57) **CLAIM**

The ornamental design for an electric spray gun, as shown and described.

DESCRIPTION

FIG. 1 is a perspective view of an electric spray gun showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in FIGS. 1-8 show portions of the electric spray gun that form no part of the claimed design. The dot-dash broken line in FIGS. 1-4, 6 and 8 defines the boundary of the claimed design, which extends to the boundary but does not include the boundary.
